US0D1086568S

(12) **United States Design Patent** (10) **Patent No.:** **US D1,086,568 S**
(45) **Date of Patent:** **** Jul. 29, 2025**

(54) **COVER FOR HAND DRYER**

(71) Applicant: **HOKWANG INDUSTRIES CO., LTD.**, New Taipei (TW)

(72) Inventor: **Cing-Fong Jheng**, New Taipei (TW)

(73) Assignee: **HOKWANG INDUSTRIES CO., LTD.**, New Taipei (TW)

(**) Term: **15 Years**

(21) Appl. No.: **29/876,103**

(22) Filed: **May 16, 2023**

(51) **LOC (15) Cl.** **28-03**

(52) **U.S. Cl.**

USPC **D28/54.1**

(58) **Field of Classification Search**

USPC D28/54.1, 58; D23/357, 361, 358

CPC A45D 29/20; A47K 10/48; A47K 10/485;

F24H 3/041; F24H 3/00; F24H 3/02

(57) **CLAIM**

The ornamental design for a cover for hand dryer, as shown and described.

DESCRIPTION

FIG. 1 is a perspective view of a cover for hand dryer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.
